UNITED STATES PATENT OFFICE.

EMERY BAYARD, OF ROCHESTER, NEW YORK, ASSIGNOR TO UNITED SHOE MACHINERY COMPANY, OF PATERSON, NEW JERSEY, A CORPORATION OF NEW JERSEY.

METHOD OF MAKING SHOES.

No. 855,831.

Specification of Letters Patent.

Patented June 4, 1907.

Application filed October 3, 1906. Serial No. 338,001.

To all whom it may concern:

Be it known that I, EMERY BAYARD, a citizen of the United States, residing at Rochester, in the county of Monroe and State of New York, have invented certain Improvements in Methods of Making Shoes, of which the following description, in connection with the accompanying drawings, is a specification, like reference characters on the drawings indicating like parts in the several figures.

This invention relates to the manufacture of boots and shoes and particularly to a novel method of conforming a shoe to a last.

In fitting a shoe to its last it is important that the upper materials should be conformed accurately to the shape of the end and side faces of the heel portion of the last. This must be effected to a large extent by straining the upper lengthwise of the last, or from heel end toward toe end. This is necessary because there is little opportunity to strain the upper upwardly at this part of the shoe owing to the fact that the rear portion of the upper is free to move on the last when pulled in the direction of the height of the last, and consequently such upward straining would tend to displace that portion of the upper. In making shoes it has been the practice in preparing a shoe for subsequent machine operations to grasp the upper at the toe, pull it upwardly over the point of the toe of the last, and then double it back over the bottom of the last and fasten it. As a result of this procedure those portions of the upper on either side of the median line passing over the toe of the last are left relatively slack and the marginal portions of the upper stand away from the edge of the heel portion of the last, instead of hugging the last tightly as they should. The marginal portion of the upper at the heel of the shoe is therefore loose about the edge of the last when in a later operation it is bent over and secured to the innersole and it is difficult to obtain in the lasted shoe as close-fitting a heel seat as is desirable.

An important object of this invention is to obtain a more perfect fitting of an upper to the end and side faces of the heel portion of a last than has previously been obtained. I have found that by properly straining the upper lengthwise of the last it can be made to fit the end and side faces of the heel portion of

the last and that if the upper is secured to the innersole at the heel of the shoe while the upper is under such lengthwise strain it will retain the shape of these faces of the last to a very satisfactory extent when the last has been withdrawn. I also find that a shoe made in this way will hug the wearer's heel so that it will not slip up and down when in use, thus overcoming an objectionable feature found in many low-cut or Oxford shoes.

In its broadest aspects the present invention consists in engaging the upper forward of its heel end, straining it lengthwise of the last, and, while the upper is under such lengthwise strain, securing the marginal portion of the upper at the heel of the shoe. In practicing this invention the upper may be engaged for this purpose at its forward portion by grippers. The grippers will be actuated to strain the upper forwardly from the heel end of the last lengthwise toward the toe end on both sides of the last and cause it to conform to the shape of the end and side faces of the heel portion of the last and to hug closely the edge of the heel of the last. The heel stiffener, if properly tempered, will also be drawn firmly against the last, thus conforming it to the contour of the particular last upon which the shoe is being made even if the stiffener has not been previously molded to that shape of last. The upper will be secured while it is under this strain, and by so doing the edge and the heel portions of the upper will be held in the positions to which they have been drawn. Prior to securing the upper the lining, heel stiffener, and upper will preferably be adjusted as may be found necessary into their proper vertical positions with relation to each other and to the last. While the upper is under lengthwise strain its rear portion will preferably be pressed or drawn over upon the innersole at the sides of the heel of the last near the front ends of the heel stiffener and tacked to the innersole to secure the upper and stiffener in proper relation to the last at these points. For the best results a tack will also be driven into the rear end of the last to secure the upper and heel stiffener to the last at that point. This tack prevents any vertical displacement of the upper materials on the heel end of the last and it may advantageously pass through the heel stiffener near the upper

edge of the stiffener, which is usually above the rearmost point on the last. A tack driven near the upper edge of the heel stiffener prevents the stiffener from springing away from the last when the lengthwise strain on the upper has been discontinued. In most kinds of work the upper and stiffener will also preferably be forced over the inner-sole at the rear end of the shoe and tacked to the innersole at that point as usual. If desired, the upper may be pressed or drawn over the innersole and secured at other points about the heel and thus the heel of the shoe may be more or less completely lasted while the upper is still held under lengthwise strain. It is preferable to pull the upper in a vertical plane which lies in or is approximately parallel to the longitudinal axis of the last and which is so predetermined that it will not be affected by variations in the relative elasticity of the upper at the two sides of the shoe. Pulling the upper lengthwise of the last as described draws the upper forwardly over the inclined instep portion of the last, causing it to fit approximately this face of the last, and this effect is increased by pulling the upper slightly upwardly as it is strained forwardly.

One of the advantages gained by pulling the upper lengthwise as described, is that some of the stretch is taken out of the upper and in particular the upper is stretched longitudinally so that it is unnecessary to cut the upper as long as would otherwise be required, thus effecting a saving in upper stock. While it is preferable to strain the upper slightly upwardly as stated, it is important that the upper be not bent upwardly over the toe of the last to any extent that would substantially relax the tension on the edge of the upper at the rear part of the shoe before the upper is secured. For the best results the grippers or other pulling means will be broad enough to engage a sufficient width of the upper to insure that the side portions of the upper shall be well strained lengthwise as well as the portion of the upper along the median line of the shoe.

The upper may be pulled with relation to a gage and stretched lengthwise to locate the toe tip seam or other part in desired relation to the last. Preferably when this is to be done the upper will be pulled with relation to a gage or gages located on each side of the shoe. The position of the seam upon the gage will be observed after it is pulled and if the seam is not in correct position—as, for example, if it is drawn too far ahead or not far enough—the strain will be decreased to allow the upper to contract or will be increased to stretch the upper more. If the seam does not extend straight across the shoe, or in other desired direction, as indicated by the fact that one end of the seam is farther ahead on the gage than the other,

then the upper may be shifted longitudinally about the last by turning the last about its pivotal support on the usual heel pin; or, if necessary, the pulling means will be released and re-engaged with the upper at a different place for applying different relative longitudinal strains to the two sides of the upper for straightening the seam.

A further advantage resulting from straining the upper lengthwise as described is that the lining is straightened out and freed from wrinkles so that there is less danger of a wrinkle being worked into the lining of the lasted shoe.

The invention will be more fully explained in the following description, reference being had to the accompanying drawings, in which is shown one form of apparatus by the aid of which the invention may be practiced. That apparatus is not herein claimed, as it forms the subject-matter of my pending application Serial No. 317,257, filed May 17, 1906.

Figure 1 is a side elevation of the apparatus, showing a shoe in position to be operated upon, the fore part of the upper being engaged by the grippers preparatory to pulling it lengthwise. Fig. 2 is a plan view of the shoe shown in Fig. 1. Fig. 3 is a side elevation of the shoe when it has been pulled, the arrows indicating approximately the lines in which the strain has taken effect on the upper. Fig. 4 is a plan view of the shoe shown in Fig. 3. Fig. 5 is a perspective view of the shoe after the upper has been secured to the innersole at the sides of the heel in the region of front ends of the heel stiffener. Fig. 6 is a plan view of a turn shoe pulled with relation to gages which are located at each side of the shoe to show the position of the toe tip seam. Fig. 7 is a plan view of the shoe after the upper has been forced over the edge of the sole at the front ends of the heel stiffener and at the rear end of the heel and secured at these points while held under lengthwise strain.

The apparatus herein shown for use in practicing my novel method comprises a standard 2 having a heel pin 4 to receive the last and a forwardly projecting arm 6 in which the grippers are movable along a path which extends lengthwise of the last. The grippers comprise a member 8 which slides upon the arm 6, said member being provided with guides 10 and 12 above and below the arm. A co-operating gripper member 14 is pivoted at 15 to the member 8 and a chain 11 extends from the lower end of the member 14 over a pulley 16 on a downward extension of the guide 12 and from thence upwardly over a pulley 18 on the guide 10. From pulley 18 the chain passes rearwardly and downwardly over a pulley 20 on the end of the arm 6 to a foot treadle 22 which is pivoted to the standard 2 and has a pawl 23 to co-operate with a

ratchet 24 fixed to the standard, all as shown in Fig. 1. The parts are constructed and arranged so that when the treadle is depressed the gripper member 14 is rocked to engage the upper and in the further depression of the treadle the gripper members are moved together along the arm 6 and pull the upper lengthwise of the last from the heel end thereof forwardly, and preferably, slightly upwardly. A gage 30 may be applied at either side of the arm 6 if desired, as shown in Fig. 6. The graduations on the gage indicate the position of the toe tip seam and enable the operator to see if the seam extends in the desired direction across the toe of the last. In practicing the invention with the apparatus shown, the upper materials, with the heel stiffener in position between the lining and the upper, if desired, may be placed over the heel pin 4 and the toe of the upper inserted between the grippers. The treadle will then be depressed and the grippers thereby closed and then moved outwardly on the arm 6 to straighten and hold the upper. A last with an innersole or sole applied to its bottom face will next be inserted in the upper and placed over the heel pin, the upper being relatively adjusted vertically to cause its marginal portion to project the desired distance above the last bottom. The heel stiffener may also be put into position at this time, if desired, instead of before the upper is applied to the machine. It will of course be understood that the particular manner of assembling the upper materials and placing them and the last in position for the upper to be strained lengthwise is not important and may be left to the preference of each operator. The parts having been put into positions as described, movement of the grippers outwardly on the arm 6 will cause the upper to be strained and stretched lengthwise of the last in a substantially right line. For the best results the upper should not be drawn into contact with the top face of the toe of the last to an extent that would substantially relax the tension on the marginal edge of the upper at the heel end of the last. The effect of this lengthwise straining is to draw the rear portion of the upper against the end and side faces of the heel, causing it to conform to the shape of the heel portion of the last from the edge of the last downwardly toward the cone of the last. The heel stiffener will also be shaped into close conformity with the contour of the last by the pressure of the upper about it. The arm 6 is preferably arranged to guide the grippers in a path which lies approximately in a plane extending vertically through or substantially parallel with the longitudinal axis of the last, by which is meant the axis extending from the extreme heel end to the extreme toe end of the last.

Preferably the grippers are moved for straining the upper lengthwise in a path the

direction of which is not affected by variations in the elasticity of the two sides of the upper. In the apparatus shown the vertical plane in which the path is located is determined by the guide slot in the arm 6. This insures that the upper shall be pulled straight ahead and through the same distance at both sides of the shoe so that the tip seam will not be drawn farther forward on one side than on the other if the upper is more elastic on one of its sides than on the other as is frequently the case.

As herein shown the upper is pulled slightly upwardly as it is pulled forwardly, the arm 6 of the illustrated apparatus being inclined as shown in Fig. 1. By this arrangement the upper, having been positioned vertically with relation to the heel of the last, is first drawn into engagement with the last near its upper edge, and the area of firm engagement spreads downwardly along the rear end of the last as the grippers move forwardly and upwardly. Pulling the upper in this direction also permits it to be drawn over the inclined face of the instep of the last with the least friction, while greater friction holds the upper against reverse movement by reason of its contraction after the securing tacks have been driven and the grippers released.

It is preferable that the gripping jaws be wide enough, as shown for example, to engage a considerable portion of the upper and exert a pull on the sides of the vamp rather than that they be so narrow that the strain would be directed largely to the upper in the median line of the shoe.

When the upper has been sufficiently pulled to cause it to fit the heel portion of the last snugly and has been longitudinally stretched to the desired extent the pawl 23 will be engaged with the ratchet 24 by a side-wise movement of the foot treadle 22, thus locking the grippers and holding the upper under lengthwise strain, as shown in Figs. 3 and 4. The operator may observe the position of the toe tip seam at the two sides of the shoe and, if necessary, he will manipulate the grippers to move the seam forwardly or backwardly, or will turn the last about the heel pin to change the relative strain on the two sides of the upper for straightening the seam. In some instances it may be necessary to release the grippers and re-engage them at a different point in order to draw the tip straight on the last. If the gage 30 is used as shown in Fig. 6 the correct position of the seam may be ascertained by its relation to the gage. While the upper is held under lengthwise strain with its edge taut it will be secured to the innersole at the heel end of the last. Preferably the upper will be pressed or pulled over the innersole at the sides of the heel and secured at or near the ends of the heel stiffener. Prior to doing this it is usually necessary to adjust the ends of the stiff-

ener vertically, particularly if a "straight" or flangeless stiffener is used, to cause the break or bend for forming the flange to be made at the right place, and it is frequently desirable to pull up the lining to remove wrinkles extending lengthwise in it. The upper, the flange of the stiffener and the lining are then forced over the last bottom at each side of the shoe and all secured to the innersole by 10 tacks, as 25, which are driven fully into the stock where they may form a part of the means for permanently fastening together the parts of the shoe. It is desirable also to drive a tack 26 into the rear end of the shoe 15 as shown in Fig. 7, where it will pass through the heel stiffener near its upper edge. This tack holds the parts of the upper from moving vertically on the heel end of the last and it also prevents the stiffener from springing 20 away from the last when the grippers are disengaged from the upper or when the stiffener dries. In most kinds of work the upper materials will also preferably be forced over the rear end of the innersole and secured thereto 25 by a tack 27 as shown in Fig. 5 while the upper is still under lengthwise strain.

It will be observed by comparing Figs. 3 and 4 with Figs. 1 and 2 that while portions of the upper below the bottom of the inverted last are stretched and caused to conform to the contour of the heel portion of the last throughout its height, the marginal portion of the upper extending above the last bottom is stretched less than the other portion and is caused to lie over the edge of the last where it may be very readily bent down upon the last bottom in position to be secured. The marginal portion of the upper at the heel thus presents a minimum of fullness 30 to be taken care of in forcing it into lasted position upon the heel seat end of the innersole so that a smoother heel seat may be produced in the lasted shoe than if the marginal portion of the upper were loose about the edge of the last. While I have shown in Fig. 35 one tack, 25, located in each side of the heel at the forward portion of the heel stiffener it is of course within the invention to insert any desired number of tacks or other securing 40 devices for fastening the upper while it is held under lengthwise strain. The upper might, if desired, be turned down upon the innersole and secured around the entire heel portion of the shoe bottom. When the upper 45 has been secured the treadle of the machine will be disengaged from the ratchet 24 and the grippers permitted to slide backwardly on the arm 6 to release the upper.

It is found in practice that by straining the 50 upper lengthwise of the last as described the stretch is taken out of the upper more or less, which is desirable. One advantage resulting from thus stretching an upper lengthwise is that it is practical to cut uppers somewhat shorter than when the shoes are made as

heretofore, thus effecting a saving in upper stock.

It will be understood that my novel method is not limited to practice by means of the apparatus herein shown and described, as that apparatus is illustrated and its use is described merely for the purpose of showing one way in which the method may be practiced. The invention is, of course, not limited to any apparatus and the performance of the 75 succession of steps in which my improved method consists is within my invention in whatsoever manner or by whatsoever means those steps may be performed.

Having explained the nature of this invention and fully described how it may be practiced, I claim as new and desire to secure by Letters Patent of the United States:

1. The method of making shoes which consists in engaging the forward portion of an 85 upper, pulling it lengthwise of a last and holding it under lengthwise strain; and adjusting and securing parts of the shoe at the heel end of the last while the upper is so held under lengthwise strain.

2. The method of making shoes which consists in straining an upper in a lengthwise direction along a last in a substantially right line, and securing parts of the upper at the heel end of the last while the upper is held 95 under such lengthwise strain.

3. The method of making shoes which consists in straining an upper forwardly to conform its rear portion to the end and side faces and the edge of the heel portion of a last, and securing the rear portion of the upper at the sides of the heel while the upper is held under such strain.

4. The method of making shoes which consists in engaging the forward portion of the upper, pulling the upper forwardly and thereby straining it lengthwise of the last, holding the upper with its marginal portion under lengthwise strain, and bending the edge of the rear portion of the upper over the last bottom and securing it while the upper is held under such strain.

5. The method of making shoes which consists in engaging the toe portion of the upper, pulling the upper lengthwise of the last, holding it with its marginal portion under lengthwise strain, and lasting the heel portion of the shoe while the upper is under such strain.

6. The method of making shoes which consists in applying an upper to a last, straining the upper forwardly along the edge of the last and upwardly along the instep of the last, forcing the upper inwardly over the innersole at the sides of the heel, and securing the upper to the innersole while the upper is so held under strain.

7. The method of making shoes which consists in positioning an upper on a last, engaging the fore part of the upper, pulling the upper lengthwise of the last and upwardly but 130

without bending it over the toe of the last, and securing the upper at the heel end of the last while it is held under such lengthwise strain.

5 8. The method of making shoes which consists in engaging the forward portion of an upper; pulling it lengthwise of a last; securing parts of the shoe at the heel end of the last while the upper is held under such lengthwise strain; and then releasing the forward portion of the upper.

9. The method of making shoes which consists in straining an upper lengthwise of a last, and securing the upper and heel stiffener 15 to the innersole at the sides of the heel portion of the last and also fastening the upper and stiffener to the rear end face of the last while the upper is held under such lengthwise strain.

20 10. The method of making shoes which consists in engaging the forward portion of

an upper and pulling it lengthwise of a last, relatively moving the last and upper to adjust the upper longitudinally about the last, and securing the upper at opposite sides of 25 the heel of the last while the upper is held under such lengthwise strain.

11. The method of making shoes which consists in engaging the forward portion of an upper and pulling it lengthwise of a last, 30 positioning the toe tip seam with relation to a gage and securing the upper at the heel end of the last while the upper is held under such lengthwise strain.

In testimony whereof I have signed my 35 name to this specification in the presence of two subscribing witnesses.

EMERY BAYARD.

Witnesses:
